UNITED STATES PATENT OFFICE.

JOHN S. HUNT, OF RICHMOND, INDIANA.

IMPROVEMENT IN HOOK-AND-LADDER APPARATUS.

Specification forming part of Letters Patent No. 128,882, dated July 9, 1872.

Specification describing certain Improvements in Hook-and-Ladder Apparatus, invented by JOHN S. HUNT, of Richmond, Indiana.

My invention relates to a plan of so constructing apparatus for carrying ladders that each ladder is held in a separate compartment with its breadth in a vertical position, being run in and out on rollers, and thus affording much greater convenience in loading and unloading than by the ordinary method of piling the ladders one upon another. I have devised two plans for locating and arranging the rollers, both of which are shown in the drawing.

Figure 1 is an end elevation of the compartments with the ladders inserted. Fig. 2 represents a cross-section of a ladder-rail, to which is attached a bearing in which rollers are held, including the rollers and braces for supporting a way. Fig. 3 represents a section, showing another plan of locating the rollers.

The parts *b*, *d*, and *s* constitute a frame, several of which are located at intervals along the length of the carriage, and are united, according to one plan, by ways *u*, upon which latter

the rollers *n* play in running the ladders in and out, the ways being supported by brace *c e*. The frames thus compose the compartments. The parts *a i* represent the ladders.

According to the plan represented in Figs. 1 and 2 the bearings *v* are bolted to the inside of the rail, thus making the rollers a part of the ladder, pairs of said rollers being located at intervals along one rail of a ladder.

The other plan of locating the rollers, as shown in Fig. 3, consists in placing a roller, *j*, at the bottom of each compartment, over which the lower rail of the ladder runs in loading and unloading said ladders. This plan allows the brace *c e* to be dispensed with.

Having thus fully described my said invention, what I claim, and desire to secure by Letters Patent, is—

The vertical compartments, arranged to hold the ladders separately, with their breadths in a vertical position, substantially as described.

JOHN S. HUNT.
